(57) **CLAIM**

The ornamental design for a martial arts training device, as shown and described.

DESCRIPTION

FIG. 1 is a front perspective view of the martial arts training device;

FIG. 2 is a front view of the martial arts training device;

FIG. 3 is a rear view of the martial arts training device;

FIG. 4 is a right side view of the martial arts training device;

FIG. 5 is a left side view of the martial arts training device;

FIG. 6 is a top side view of the martial arts training device;

FIG. 7 is a bottom side view of the martial arts training device; and,

FIG. 8 is a front perspective environmental view of the martial arts training device.

In FIG. 8, the broken lines are for the purpose of showing additional equipment that can be attached to the device that form no part of the claimed design.

1 Claim, 8 Drawing Sheets
